SLAT FOR VENETIAN BLINDS AND METHOD
OF MAKING

George D. Dodge, Evanston, Ill.

Application September 24, 1934, Serial No. 745,221

13 Claims. (Cl. 156—17)

This invention relates to venetian blinds, and particularly to venetian blind slats.

The primary object of the invention is to provide a very attractive, highly ornamental venetian blind slat, which is provided with contrasting surfaces of pleasing and ornamental appearance, and which has great light deflecting or diffusing capabilities and qualities.

Another object of the invention is to provide a venetian blind slat having a wood, painted or lacquered surface on one side, and a smooth highly polished metal surface on the other side, whereby a great contrast is presented between the two surfaces to produce a pleasing highly ornamental effect.

A further object of the invention is to provide a laminated venetian blind slat having a wood or composite body portion and a metal inlaid or metal covered portion fastened thereto.

A still further object is to provide a laminated slat and the method of fastening the laminations together, so as to produce a slat having surfaces thereof made of different materials to present a contrasting appearance.

Another object of the invention is to provide a laminated blind slat which is made of a material or materials so as to prevent the slats from producing a rattling sound, and which if engaging each other do not make any sound, or at the most, a dead sound.

Numerous other objects and advantages will be apparent throughout the progress of the following specification.

The accompanying drawing illustrates a selected embodiment of the invention, and the views therein are as follows:

Fig. 1 is a detail perspective view of a venetian blind, and embodying the invention, the slats being arranged in flat horizontal position.

Fig. 2 is a view similar to Fig. 1, but showing the slats in tilted position.

Fig. 3 is a detail transverse sectional view of a venetian blind slat shown in Figs. 1 and 2.

Fig. 4 is a detail sectional view similar to Fig. 3, but on a greatly enlarged scale.

Figs. 5, 6 and 7 are detail sectional views of modified forms of slats.

It is highly desirable to provide venetian blind slats with contrasting surfaces. At the present time, there is a large demand for venetian blinds for the purpose of attractively displaying wares in show rooms and show windows, where a venetian blind having contrasting but harmonizing surfaces is desired to fit in with the color scheme of the display. For instance, a display window

arranged to display a piano produces a pleasing effect which is instantly caught by the eyes of the passersby as when a highly polished chromium plated venetian blind is positioned behind the piano. A straight, flat, reflecting surface such as a mirror would not attain this pleasing effect, nor would it attract the eye as rapidly, because of the conventional use of mirrors. Therefore, by making the slats of the venetian blind of contrasting colors or materials, an entirely different effect is produced which is pleasing to the aesthetic faculties. Furthermore, when the blind is used in an opening such as a window opening, it is desirable that the blind have high light diffusing or deflecting characteristics. A venetian blind constructed in accordance with the present invention therefore, can diffuse the outside light without darkening the room, or if desired, the blinds can be tilted so that the bright light is diffused, and the soft plain color of the remaining part of the blind will be visible. In large dining rooms, banquet halls, and other places, a very desirable and ornamental effect is produced if one side of the blind is highly polished metal, and the other side has a painted color applied thereto, which makes a sharp contrast to the polished metal surface. If the slat supporting tapes are the same color as the painted or lacquered portions of the blind, the contrast and the color scheme is considerably enhanced.

Another type of venetian blind slat wherein a fibrous filler is surrounded by a sheet metal covering is disclosed and claimed in applicant's co-pending application Serial No. 724,941, filed May 10, 1934.

The present invention, therefore, relates to the manufacture and assembly of venetian blinds and slats thereof which have a metal surface on one side, and a wood or composite portion of a contrasting color on the other side.

In the accompanying drawing there is shown a venetian blind having a plurality of slats 10 carried by tapes 11 which support the slats, and which hold the slats in proper spaced relationship. The slats may be provided with cord receiving openings 12 through which the blind operating cords 13 pass for operating the blind in the usual conventional manner. The blind is provided with the usual tilting bar for tilting the slats through various angles in accordance with the movement of the tilting bar.

The slats 10 each have contrasting surfaces 14 and 15. In the drawing, the upper surface 14 of the slats comprises a metal strip 16 which is mounted on the upper side 17 of the lower por-

tion 18. The lower portion 18 may be of wood, fiber, or any composite material, and is adapted to have the upper metal surface 16 applied thereto. The upper surface 16 is preferably formed 5 of relatively thin sheet metal which may be plated with any suitable material such as chromium. As shown in Figs. 1 to 4, the bottom part or base 10 of the slat more clearly shown in Fig. 4, may be recessed as indicated at 19 to provide an opening into which the upper portion 16 of the slat is received. The upper portion 16 of the slat is 15 preferably formed around a filler 20. The filler may be any fibrous material such as wood, cardboard, and the like, with the sheet metal fixed thereto, bent around the edges thereof as indicated at 21, and lapped about the under surface as indicated at 22. If the metal is of any appreciable thickness, the bottom member 18 may be provided with an additional recess 23 to receive the overlapping portion or flange 22. The recess 19 extends inwardly from the edges 24 of the slats a predetermined distance to provide an edge which is of the same material as the bottom portion of the slat. The metal portion 16 25 and its filler 20 may be fastened to the upper surface 17 by a proper adhesive 25. This construction provides a venetian blind having a lower surface 18 and edges 24 made of one material such as wood, which may be painted or lacquered 30 any color desirable. The metal surface 16 provides a highly polished metallic appearing surface which is in sharp contrast with the remaining portion of the slat. Thus, when the slat is in the position shown in Figs. 1 and 2, a considerable portion of polished metal is presented, but this metal surface is broken up by the horizontal lines of contrasting color due to the appearance 35 of the end edges 24.

In the modification shown in Fig. 5, the slat 40 10 comprises a bottom fibrous portion 30 such as wood, which is recessed at 31 to receive the bottom flange 32 of the plated metal upper surface 33. The outer edge 34 of the metal may extend 45 about the edge of the slat a distance substantially equal to one-half thickness of the finished slat, whereby the edges of the slat provide the metal portion 35 and the painted or colored portion 36. The metal covering 33 is formed about a central filler member 37 which is adhesively or otherwise fastened to the bottom portion of the slat 50 as indicated at 38.

In Fig. 6 the bottom portion 40 of the slat 10 is relatively flat, the metal portion 41 being formed around the filler 42 with the flange 43 recessed into the filler. The upper portion and lower portion of the slat are adhesively fastened together as indicated at 44. The slat shown in Fig. 6, like the slat shown in Fig. 5, provides an edge having contrasting portions 45 and 46.

Instead of forming the metal surface about a 60 filler and then fastening the filler to a bottom wooden portion, a metal strip 50 may be imbedded in a slat 51 formed of composite material, Fig. 7. The composite slat portion 51 may be of any material practical or desirable, such as impregnated 65 wood or bakelite, and the upper metal surface 50 may be imbedded therein during the formation or treatment of the slat. One way of forming the slat, is to mold the slat of composite material and insert the metal in the mold and 70 then mold the composite material, whereby the metal portion may be an integral part of the finished slat. Another way of producing the slat shown in Fig. 7 is by making a slat from suitable fibrous material such as wood or card-

board, and then impregnating or treating the slat with a suitable substance, the substance causing the metal to adhere tightly to the slat. One material well known on the market is "Catalan." This material impregnates the wood or fibrous 5 material and forms a tight adhesive bind between the metal and the balance of the slat, rendering the slat water-proof and preventing warping.

Regardless of how the slat is constructed, or from which materials the slat is made, the invention provides the means and method of producing a highly ornamental slat of pleasing appearance having a polished metal surface on one side and a contrasting painted surface on the other side. The slats are light in weight, and due 10 to the manner in which they are constructed and laminated, do not have the usual rattling or clattering sound, but instead have a dead sound. Slats made in accordance with this invention can be very economically constructed, 15 and they are very light in weight, while at the same time are relatively strong and durable in construction.

Changes may be made in the form, construction and arrangement of the parts without departing from the spirit of the invention, or sacrificing any of its advantages, and the right is hereby reserved to make all such changes which fairly fall within the scope of the following claims.

The invention is hereby claimed as follows:

1. A venetian blind slat having a metal surface member on one side thereof, and a surface member of contrasting material and color on the other side thereof, a filler member arranged between said surface members, and means for fastening said filler and said surface members together.

2. A venetian blind slat having a metal surface on one side thereof, and a surface member of contrasting material and color on the other side thereof, said metal surface having a portion thereof bent inwardly, means under the metal surface and within the bent portion, and means for fastening the said means to said surface member of contrasting material.

3. A venetian blind slat comprising a bottom member having a recess formed therein, an upper member arranged in said recess, and means for fixing said two members together.

4. A venetian blind slat comprising a bottom 50 member having a recess formed therein, a metal surface member arranged in said recess, and means for fastening the members together.

5. A venetian blind slat comprising a filler member, a metal sheet about one side of said 55 filler member and extending over the ends thereof of a lower member of different material, and means for fastening the filler member to the lower member.

6. A venetian blind slat comprising a filler 60 member, a metal sheet about one side of said filler member and extending over the ends thereof, another member of different material arranged adjacent the filler member, and means for fastening said last two named together.

7. A venetian blind slat comprising a metal sheet, a filler member to which the sheet is fastened, and an additional member fastened to said 65 filler member.

8. A venetian blind slat having a bottom member, and a metal strip imbedded in said member.

9. A venetian blind slat comprising a body member made of composite material, and a metal strip imbedded in said composite member, said strip being fastened to said composite member by 75

- the adhesive characteristics of the composite member.
10. A venetian blind slat comprising an elongated body member having a longitudinally extending groove therein, and a sheet metal strip on said body having a portion lying within said groove. 5
11. A venetian blind slat comprising an elongated body member having a longitudinally extending groove therein, and a sheet metal strip on said body, said strip having crimped-over portions embedded within said groove. 10
12. The method of making a venetian blind slat which comprises preforming a longitudinal groove in one face of an elongated body member, applying a metal strip to said body, embedding portions of said strip within the groove and securing said body and metal strip together by an adhesive. 5
13. A venetian blind slat made of a predetermined fibrous material, and a sheet metal strip imbedded in said slat. 10
